DESIGN FOR A COMBINED PENDANT WALLET AND DOG TAG HOLDER

Harold J. Lyon, Los Angeles, Calif.

Application June 3, 1943, Serial No. 110,358

Term of patent 3½ years

To all whom it may concern:

Be it known that I, Harold J. Lyon, a citizen of the United States of America and a resident of the city of Los Angeles, in the county of Los Angeles and State of California, have invented a new, original, and ornamental Design for a Combined Pendant Wallet and Dog Tag Holder, of which the following is a specification, reference being had to the accompanying drawing, forming part thereof.

In the drawing:

Fig. 1 is a front view of a combined pendant wallet and dog tag holder showing my new design with the wallet in closed position;

Fig. 2 is a fragmentary side view thereof with part of the chain broken away for convenience of illustration;

Fig. 3 is a rear view of Fig. 1; and

Fig. 4 is a view showing the wallet in Figs. 1, 2, and 3 in open position with parts broken away for convenience of illustration.

I claim:

The ornamental design for a combined pendant wallet and dog tag holder, substantially as shown.

HAROLD J. LYON.
